(57) **CLAIM**

The ornamental design for a continuous positive airway pressure therapy device, as shown and described.

DESCRIPTION

FIG. 1 is a frontal perspective view of a continuous positive airway pressure therapy device with an optional mouth piece and a cap portion illustrated in broken lines;

FIG. 2 is a left end elevational view of the continuous positive airway pressure therapy device;

FIG. 3 is a frontal elevation view of the continuous positive airway pressure therapy device with a cap illustrated in broken lines, but not forming a part of the invention;

FIG. 4 is a right end profile view of the continuous positive airway pressure therapy device;

FIG. 5 is a bottom elevational view of the continuous positive airway pressure therapy device; and,

FIG. 6 is a top elevational view of the continuous positive airway pressure therapy device.
